UNITED STATES PATENT OFFICE.

ISAAC HUTCHINS, JR., OF WELLINGTON, MAINE.

IMPROVED FUMIGATOR.

Specification forming part of Letters Patent No. 59,025, dated October 23, 1866.

To all whom it may concern:

Be it known that I, ISAAC HUTCHINS, Jr., of Wellington, Piscataquis county, and State of Maine, have invented a new and Improved Fumigator; and I do hereby declare that the following is a full, clear, and exact description thereof, which will enable others skilled in the art to make and use the same, reference being had to the accompanying drawing, forming part of this specification, in which—

Figure 1 is a longitudinal central section of my improved fumigator.

My invention has for its object to furnish an improved instrument for destroying lice and ticks upon sheep and cattle by fumigating them with tobacco-smoke; and it consists, first, of the cylinder or box for containing the burning tobacco, in combination with the bellows; and, second, in the combination of a perforated plate with the cylinder or box, for the purpose of preventing the tobacco from passing into and clogging the discharging-orifice of the said cylinder.

A is the bellows, which is formed of two circular disks, a^1 and a^2 , connected together at their edges by a leather or other flexible band, as shown in the drawing. To the center of one of these disks, a^1 , is attached a handle, a^3 , by means of which the bellows A is operated. To the center of the other disk, a^2 , is attached a pipe, a^4 , through which the blast escapes from the bellows.

a^5 is the valve which, as the disks are drawn apart in operating the bellows, opens to admit the air, and as the disks are pressed together closes, and the air is forced out through the pipe a^4 . The outer end of the

pipe a^4 is enlarged into a cap, as shown in the drawing, into which is screwed the end of the cylinder or box B, as shown. This cylinder or box is made of sufficient size to hold the desired amount of tobacco. The outer end of the cylinder or box B is contracted into a nozzle, b' , with a small discharging-orifice, as shown.

C is a perforated plate or wire sieve inserted in the cylinder B just above the nozzle b' , as shown, so as to prevent the tobacco from entering the said nozzle and clogging the discharging-orifice.

In using the apparatus, the cylinder B is filled, or partially filled, with tobacco and lighted upon the top. The bellows A is then operated, which forces the smoke out through the nozzle b' .

In fumigating sheep the nozzle b' is inserted in the wool and moved from place to place till the whole fleece is filled with the smoke. The instrument may also be used for destroying insects on plants and trees by smoking them in the manner described.

I claim as new and desire to secure by Letters Patent—

1. The cylinder or box B, constructed as described, in combination with the bellows A, substantially as described, and for the purpose set forth.

2. The combination of the perforated plate C with the cylinder or box B, substantially as described, and for the purpose set forth.

ISAAC HUTCHINS, JR.
